EDWARD R. THOMPSON, OF ST. LOUIS, MISSOURI, ASSIGNOR TO ST. LOUIS TIN AND SHEET METAL CO., OF ST. LOUIS, MISSOURI, A CORPORATION OF MISSOURI.

POURING-SPOUT.

1,223,533.

Specification of Letters Patent.

Patented Apr. 24, 1917.

Application filed July 10, 1916. Serial No. 108,408.

To all whom it may concern:

Be it known that I, EDWARD R. THOMPSON, a citizen of the United States, residing at St. Louis city, State of Missouri, have invented a new and useful Pouring-Spout, of which the following is a specification.

The present invention relates to a pouring spout for cans.

The object of the invention is to provide a pouring spout, which may be quickly applied to the usual screw-threaded nozzle of sheet metal cans, and which may be easily adjusted thereon into and out of pouring position.

15 The invention comprises a pouring lip provided, at its inner end, with a channeled ring or collar, adapted to fit around the nozzle of a can, and support the lip. The channeled collar is adapted to catch and hold the return flow of the liquid from the pouring lip, and the overflow of the liquid from the top of the nozzle, when the can is set upright after pouring. The construction of the pouring spout is such that the ring or 20 collar may be turned on the nozzle to project the lip outwardly from the can for pouring, or may be turned inwardly over the top of the can out of the way when not in use.

The above and various other objects and 30 advantages of this invention will be brought out more clearly in the following specific disclosure of the present preferred embodiment of the invention, the same being illustrated in the accompanying drawing, 35 wherein—

Figure 1 is a side elevation of a pouring spout constructed according to this invention, and applied to the ordinary can nozzle, the closing cap being shown as applied to 40 the nozzle, and the dotted lines showing the pouring spout turned inwardly out of the way when not in use.

Fig. 2 is a longitudinal sectional view, enlarged, of the pouring spout as applied to 45 the can nozzle, showing the closing cap applied to the latter.

Fig. 3 is a transverse vertical section, taken through the same, the closing cap being removed.

50 Fig. 4 is a top plan view of the improved pouring spout.

Referring to this drawing, 10 designates a pouring lip, which has side flanges 11 upturned from the opposite edges of the lip 55 and converging toward the outer end of the

same. The pouring lip 10 has a channeled attaching ring or collar at its inner end, the attaching ring being composed of an inner annular flange 12, which is continuous and comprises the inner wall of the channel, and an outer flange 13, which merges into the upturned sides 11 of the pouring lip, and comprises the outer wall of the channel.

The flanges or walls 12 and 13 meet at their lower edges, and diverge upwardly to 65 form the channel, the latter being substantially V-shaped and merging into the pouring lip.

The attaching ring, or inner portion of the pouring lip 10, is adapted to fit over the 70 usual nozzle 14 of a can 15. The upper edge of the inner flange 12 snugly embraces the threads of the nozzle 14, and frictionally holds the pouring spout in adjusted position. From Figs. 2 and 3, particularly, it 75 will be noted that the inner flange 12 slopes downwardly and away from the nozzle 14, to carry the overflow liquid away from the nozzle, and into the channel to prevent the passage of the liquid downwardly between 80 the nozzle and the ring or collar.

The pouring spout may be turned to project the lip 10 outwardly, or forwardly, from the adjacent corner or side of the can, as shown in Figs. 1 and 2, into pouring position to receive liquid from the nozzle 14 when the can is tilted. As shown in dotted lines in Fig. 1, the pouring spout may be turned around on the nozzle 14 to project the lip 10 backwardly within the marginal 90 edge of the can top, and out of the way, to prevent injury to the pouring lip when the can is packed in a case, or the like.

In operation, when the can is tilted forwardly, the liquid flows out of the nozzle 14, 95 into the lip 10, and is conducted thereover between the flanges 11 to the desired point of discharge.

When the can is set upright, a quantity of the liquid overflows the upper edge of the 100 nozzle, flows down the outside of the nozzle, and is caught in the channel, and held from dripping on the top or sides of the can. The liquid remaining in the lip 10 flows back and is also caught in the channel and 105 held from dripping on the can.

The formation of these inclined flanges 12 and 13 not only provides means for catching the overflowing liquid, but also means for reinforcing or stiffening the ring.

As is apparent from the top plan view in Fig. 4, the pouring spout of this invention may be made from a single blank, which is rounded at one end and elongated and tapered at its opposite end. The marginal edge of the blank is bent upwardly along the sides of the elongated end and about the rounded end to provide the sides 11 of the pouring lip and the outer flange 13, which 5 constitutes a continuation of the sides 11. The rounded end of the blank is apertured, and the inner marginal edge is bent upwardly to form the inner flange 12, which 10 engages frictionally in the threads of the nozzle. Preferably, the sides 11 of the 15 pouring lip extend higher than the upper edge of the flange 13 to prevent the spilling of the liquid flowing over the pouring lip. It will be noted that the bottom of the channel formed by the walls 12, 13 is lower than 20 the bottom of the lip, and that the wall or flange 13 is higher than the wall or flange 12. This causes the drip to collect in the channel and it is prevented from overflowing 25 by the wall 13.

The pouring spout is adapted to be screwed down over the nozzle 14 to any desired extent, and may be turned down to the bottom of the threads of the nozzle, as 30 shown in Figs. 2 and 3, to bind the inner flange 12 upon the nozzle and thus frictionally hold the pouring spout in place.

The closing cap 16 may be screwed down 35 tightly in the usual manner, without the removal of the improved pouring spout, and without interfering with the adjustment of the same.

What is claimed is:—

1. A pouring spout for application to the nozzles of cans comprising a pouring member constructed with a pouring lip having side flanges and located at one end thereof,

and an attaching collar at its opposite end adapted to entirely surround said nozzle and support the lip thereon, said collar comprising an upwardly extending inner flange adapted to engage the nozzle and encircle the same, and an outer flange extending upwardly from the lower portion of the inner flange at the side thereof remote from said lip, merging with said side flanges and forming with said inner flange a substantially annular channel at its upper side communicating with said pouring lip and adapted to receive the return flow of liquid from the 55 pouring lip and the overflow from the top of said nozzle when the can is set in upright position.

2. A pouring spout for application to the nozzles of cans, comprising a pouring lip 60 and an attaching collar, said lip having side flanges converging toward the outer end, and said collar comprising an inner circular flange adapted to fit around the can nozzle and inclined downwardly away from said 65 nozzle, an outer flange joining with the bottom of the inner flange and inclined upwardly away from the inner flange and forming therewith a V-shaped channel, the outer flange being made higher than the 70 inner flange and extending partly around the same and merging into the side flanges of the lip, said side flanges being on a higher plane than the outer flange of the collar and 75 the bottom of said lip being also above the plane of the bottom of the said channel.

In testimony, that I claim the foregoing as my own, I have hereto affixed my signature in the presence of two witnesses.

EDWARD R. THOMPSON.
